CLAIM

The ornamental design for a hard disk storage device, as shown and described.

DESCRIPTION

FIG. 1 is a perspective view of a hard disk storage device showing our new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view of another state of the hard disk storage device thereof; and,

FIG. 9 is an enlarged view of the selected portion in FIG. 2.

The broken lines shown in the drawings depict portions of the hard disk storage device in which the design is embodied that form no part of the claimed design.
